UNITED STATES PATENT OFFICE.

HARRY MARKS AND SANFORD HELSEL, OF JOHNSTOWN, PENNSYLVANIA, ASSIGNEES
OF ONE-THIRD TO WILLIAM C. HOWLAND, OF JOHNSTOWN, PENNSYLVANIA.

INCANDESCENT-LAMP SOCKET.

1,088,914.

Specification of Letters Patent. Patented Mar. 3, 1914.

Application filed March 13, 1913. Serial No. 754,070.

To all whom it may concern:

Be it known that we, HARRY MARKS and SANFORD HELSEL, citizens of the United States, residing at Johnstown, in the county 5 of Cambria and State of Pennsylvania, have invented certain new and useful Improvements in Incandescent-Lamp Sockets; and we do declare the following to be a full, clear, and exact description of the invention, 10 such as will enable others skilled in the art to which it appertains to make and use the same.

This invention relates to improvements in sockets for incandescent electric lamps.

15 One object of the invention is to provide a socket for incandescent electric lamps having an improved construction and arrangement of locking mechanism whereby a lamp when screwed thereon cannot be removed 20 therefrom without breaking the lamp.

Another object is to provide a lamp socket of this character having means whereby the locking mechanism may be thrown out of 25 operation and the socket employed in the usual manner.

With these and other objects in view, the invention consists of certain novel features of construction, and the combination and arrangement of parts as will be more fully described and claimed.

In the accompanying drawings; Figure 1 is a central longitudinal sectional view of a socket constructed in accordance with our invention; Fig. 2 is a similar view taken at 30 substantially right angles to Fig. 1; Fig. 3 is a side view of the socket with the outer shell removed; Fig. 4 is a cross sectional view taken on the line 4—4 of Fig. 3; Fig. 5 is a similar view taken on the line 5—5 of Fig. 3 looking toward the inner end of the lamp receptacle of the socket; Fig. 6 is a detail perspective view of the spring locking pawl which is arranged on the lamp receptacle to engage and lock the plug of the 45 lamp when screwed into the receptacle.

Referring more particularly to the drawings, 1 denotes the shell or casing of the socket which may be of the usual construction except that this casing is slightly longer 50 than the casings of the usual form of sockets.

In the shell or casing 1 is arranged the usual lining or insulation of non-conducting material which insulates the casing from the lamp receptacle and other parts of the socket.

55 In the upper portion of the shell or casing

is arranged a porcelain switch supporting block 2 which may be of the usual or any suitable construction and in which is arranged the usual form of switch mechanism 3 comprising a revolvably mounted key 4 on the stem or shaft of which is the usual double ended contact member 5.

Fastened to the inner end of the block 2 is a receptacle supporting block 6 formed of porcelain or other suitable non-conducting material. The block 6 is preferably secured to the block 2 by bolts 7 which are inserted through said blocks as shown. In the outer or lower end of the block 6 is formed an annular recess 8 and in the center of the block, is formed a socket 9 and a centrally disposed bolt hole 10. Arranged at a suitable point in the recess 8 is a spring pawl 11 the inner end of which is secured in the recess 8 and to the block 6 by a bolt 12 which is passed through the block 6 and has its inner or upper end engaged with a nut 13 counter-sunk in the inner end of the block 6 and in position to be engaged by the ends of the contact member 5 of the switch key. The 75 nut, bolt and the pawl fastened thereby thus form one terminal of the circuit in which the socket is arranged when the key 4 is turned to engage the contact member 5 with the nut and inner end of the bolt. 85

Secured to the block 6 is the lamp receptacle 14 said receptacle being in the form of a thin metal socket having recessed or otherwise formed in the sides thereof a continuous thread 15 with which the threaded plug of the lamp is engaged when the latter is applied to the socket. The receptacle 14 is revolvably supported and fastened to the block 6 by a screw 16 which is engaged with an insulating disk 17 arranged in the inner end of the receptacle 14 and having a diameter corresponding substantially to that of the inner diameter of the receptacle. On the inner side of the disk 17 is a centrally disposed boss 18 which projects into and has a revoluble engagement with the socket 9 in the outer end of the block 6 as shown. On the outer headed end of the screw 16 is a metal washer 19 which with the head of the screw forms the other contact terminal of the electric circuit. The inner end of the screw 16 is engaged with a threaded aperture 20 formed in the right angular inner end of a binding plate 21 which is secured in a recess in one side of the porcelain 110

switch block 2 and which has therein a binding screw 22 with which one of the current conducting wires is connected. The opposite current conducting wire is connected with a binding screw 23 in the bracket or bearing plate 24 of the shaft of the switch key in the other terminal.

On the inner end of the lamp receptacle 14 near the outer edge thereof is formed a beveled stop shoulder 25 which is brought into engagement with the end of the spring pawl 11 when the lamp receptacle is revolved in one direction thus holding the receptacle against turning in this direction and thereby permitting the lamp to be screwed into the receptacle in the usual manner. After the lamp has been screwed into the receptacle any attempt to unscrew the lamp will revolve the receptacle in a reverse direction which movement of the receptacle will not be interfered with by the pawl as the beveled surface of the stop shoulder 25 will depress the pawl and pass beneath the same as will be readily understood.

As hereinbefore stated the pawl 11 forms one terminal of the electric circuit and as this pawl is in continuous frictional engagement with the inner end of the lamp receptacle, the latter will be connected with the circuit and the current will thus pass through the receptacle to the outer shell of the plug on the end of the lamp when said plug is screwed into the receptacle. The other connection of the lamp with the socket will be made through the usual central contact of the lamp plug with the screw 16 and washer 19 which revolvably support the lamp receptacle and attach the same to the block 6 as hereinbefore described.

In order to positively hold the threaded plug of the lamp from being unscrewed from the threaded lamp receptacle 14, we provide a spring lamp locking pawl 26 which is constructed from a coil of spring wire engaged with the corrugations or threads on the outer side of the lamp receptacle substantially midway between the ends thereof. One end of the spring pawl is bent inwardly and beveled to form a tooth 27 which projects through a slot 28 in one side of the receptacle and is adapted to engage the plug of the lamp when the latter is screwed into the receptacle. The beveled end of the tooth 27 will permit the plug of the lamp to be revolved in a direction for screwing the same into the receptacle but said end of the tooth will be caused to bite into the surface of the lamp plug when the latter is turned in a reverse direction or in a direction for unscrewing the lamp, thus positively preventing the lamp from being unscrewed from the socket as long as the receptacle 14 is loose or revolves on the socket.

In order to permit the socket to be em-

ployed in the usual manner or to permit the lamp to be unscrewed therefrom when desired, we provide means for fastening the socket against turning in the direction for unscrewing the lamp, said means comprising a set screw 29 which has a threaded engagement with a bracket 30 depending from one side of the receptacle supporting block 6. The bracket 30 is preferably formed integral with, or has its inner end bent at right angles and provided with a threaded aperture to form a nut 31 with which the inner end of one of the bolts 7 which fasten the receptacle supporting block 6 to the switch block 2 as hereinbefore described. The set screw 29 when thus arranged is adapted to be screwed inwardly and into engagement with an aperture 32 formed in one side of the lamp receptacle thereby locking the latter against turning in either direction which will thus permit the lamp to be screwed into and unscrewed from the receptacle. When the set screw 29 is disengaged from the aperture in the lamp receptacle and the latter thus left free to revolve in the manner described it will be seen that when a lamp is screwed into the receptacle and locked therein by the pawl 26 the lamp cannot possibly be removed without breaking the globe or bulb thereof which will permit the shell or casing 1 to be slipped down off from the switch block 2, receptacle supporting block 6 and lamp receptacle whereupon a suitable instrument may be inserted beneath the end of the spring pawl 26 and the tooth thereof retracted which will permit the removal of the plug of the broken lamp, while the receptacle is being held against turning by the hand as will be readily understood.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described our invention, what we claim is:

1. In an incandescent electric lamp socket, the combination with the switch supporting block and switch mechanism therefor of a lamp receptacle revolvably supported on said switch block, means to lock said lamp receptacle against turning in a direction for screwing a lamp therein, said means permitting the receptacle to be freely revolved in a reverse direction, and means to fasten said receptacle against turning in either direction.

2. In an incandescent electric lamp socket the combination with the switch supporting block and switch mechanism of the socket,

of a receptacle supporting block rigidly secured to said switch block, a lamp receptacle revolubly secured to said supporting block, a spring pawl arranged on said supporting block, a beveled stop shoulder formed on said lamp receptacle and adapted to be brought into engagement with the pawl on said supporting block whereby the receptacle is locked against turning in the direction for screwing a lamp therein but is permitted to freely revolve in the opposite direction thereby preventing the lamp from being unscrewed from the receptacle, and a set screw carried by said receptacle supporting block and adapted to be screwed into engagement with the lamp receptacle whereby the latter is locked against turning in either direction.

In testimony whereof we have hereunto set our hands in presence of two subscribing witnesses.

HARRY MARKS.
SANFORD HELSEL.
